CLARENCE W. HAZELETT, OF LAKewood, OHIO, ASSIGNOR, BY MESNE ASSIGNMENTS,
TO NATIONAL CARBON COMPANY, INC., A CORPORATION OF NEW YORK.

CASTING APPARATUS.

1,318,379.

Specification of Letters Patent.

Patented Oct. 14, 1919.

Application filed April 16, 1917. Serial No. 162,314.

To all whom it may concern:

Be it known that I, CLARENCE W. HAZELETT, a citizen of the United States, residing at Lakewood, in the county of Cuyahoga and State of Ohio, have invented a certain new and useful Improvement in Casting Apparatus, of which the following is a full, clear, and exact description.

The invention relates to casting and more particularly to an improved manner of removing molded articles from the molds. Although the invention is shown and described as it would be applied to apparatus for casting lead storage battery parts, it is not to be understood that the invention is limited thereto.

The object of the invention is to permit simultaneous casting of a plurality of articles and to facilitate the removal of the castings from the mold. In the broad aspect it consists in slicing off, as it were, a thin slab from the mold half which has the greater tendency to retain the casting, whereby an ejector plate is formed to withdraw the casting therefrom.

The objects of the invention may be attained with most types of casting machines, but the arrangement is especially advantageous when used in the manner described and illustrated in the accompanying drawings in which:—

Figure 1 is a side view of a storage battery-parts casting machine embodying the invention.

Fig. 2 is a top view of the apparatus of Fig. 1.

Fig. 3 is a section on the line A—A of Fig. 2.

Fig. 4 is a plan view of the ejector plate of Figs. 1 to 3.

Fig. 5 is a plan view of a series of spacing straps for storage battery grids.

Fig. 6 is a plan view of an ejector plate adapted to be used in casting the spacing straps of Fig. 5.

Fig. 7 is a broken cross sectional view through a mold containing the spacing straps of Fig. 5 and corresponds with the line B—B of the spacing strap.

Referring to the drawings, a stationary vertical frame 1 projects from a supporting base 2. One side 3 of the mold is secured in the upper end of the frame 1 in any suitable manner. The other side 4 of the mold 55 is fitted in a frame 5 pivoted at 6. The

frame 5 and section 4 of the mold may be turned about the pivot point 6 to separate the two parts of the mold by means of a handle 7. The handle is pivoted at 8 to projecting arms 9 attached to the stationary frame 1. The link 10 connects the end 11 of the handle with the lugs 12 which project from the movable frame 5. The mold will be opened by drawing the handle 7 downward and is closed by movement in the opposite direction.

My invention consists in placing a plate 13 between the parts 3 and 4 of the mold. This plate which will hereafter be called the ejector plate has a handle 14 on each side 70 and a plurality of openings 15 near the edges which end in narrow slots 16. (Fig. 4). The ejector plate will be attached to the side 3 of the mold by means of pins 17 fitted into the edges 18 of stationary frame 75 1. The pins have heads 18 adapted to readily pass through the openings 15 of the ejector plate and the body portion of the pins is substantially the same diameter as the width of slots 16. When the holes of the 80 ejector plate are placed over the corresponding pins so that the body of the pins fits in the slots 16, the mold cavities 19 and 20 of the mold parts 3 and 4 respectively, are aligned with corresponding openings 21 in 85 the ejector plate (Fig. 4).

To illustrate the manner in which the ejector plate is utilized, a mold for a plurality of cylindrical members is shown in Fig. 3. The openings in each side of the 90 mold are inclined to provide draft in the usual manner and the draft in the openings of the ejector plate is in the same direction as that in the movable side 4 of the mold. The various openings of part 3 of the mold 95 are connected to the gate 22 by means of passages 23 in part 3 of the mold. The cavities 20 in the retaining side 4 of the mold therefore cover less surface than the openings 21 in the ejector plate or the cavities 19 in the non-retaining side, so that parts of the article cast in the non-retaining side serve as abutments which prevent the castings from being drawn through the ejector plate by the force exerted by the retaining side of the mold. If the non-retaining side is a flat surface, then by having the openings in the ejector plate largest at the side adjacent the flat surface of the mold the same result will be obtained. To utilize the 105 110

ejector plate in accordance with the invention, the molded article is caused to have a greater tendency to stick in the mold part 4 than in mold part 3. This may be done in 5 various ways, as for example, by dusting powder on the molds to vary the sticking tendency. It is preferable, however, to take care of this by use of suitable draft on each side, or suitably locating the parting line. 10 After the molten metal has solidified the mold is divided by pulling handle 7 downward. As the sticking tendency in side 4 is greater than in side 3, the molded article will be drawn out of side 3 as the frame 5 is 15 moved. The ejector plate will also be moved along with the article and mold part 4, because the article cannot be drawn through the openings in the ejector plate by movement in this direction. The direction of the 20 draft in the ejector plate, has well as the material in gate 22 and passages 23, prevents the article from being removed except from the side 3 of the mold. When the side 4 and ejector plate 13 move through a 25 distance sufficient to remove the articles from mold part 3, the heads 18 of the pins 17 engage the ejector plate 13 and prevent it from further movement. The article will then be held by the ejector plate, and is thus 30 pulled out of the movable side 4 of the mold. This separates the articles from both sides of the mold and leaves them in the ejector plate which is supported on pins 17. The operator removes the articles by grasping 35 the handles 14 and raising the plate so that the heads 18 of the pins pass through the openings 15, and then tipping the plate so that the articles drop out. It will be evident that the use of slots and retaining pins or 40 other means for separating the articles from side 4 is not absolutely essential, as this may be done by removing the ejector plate and articles by means of the handles 14.

In casting a spacing strap for storage 45 battery grids such as shown in Fig. 5, one side of the mold having the gate 22 is flat and the draft is all in one direction. The sticking tendency on side 3 is therefore very slight. After the lead has been poured in 50 the mold and solidified, the side 4, the articles and the ejector plate all move away from side 3 until the heads of the ejector pins 17 engage the ejector plate as previously described. The ejector plate is shown 55 as having draft in a direction which prevents the articles from being removed from the retaining side of the mold, but it will be evident that connecting webs or other configurations in mold part 3 may serve the 60 same purpose so that draft will be unnecessary in the ejector plate.

Although I have only described my invention as applied to relatively simple articles, it will be evident to one skilled in 65 the art that it is capable of many modifica-

tions and elaborations, and the invention is limited only by the scope of the claims.

Having described my invention, what I claim is:

1. In apparatus for molding articles, a 70 mold divided into two parts, one of said parts having suitable recesses therein, and an ejector plate between said parts extending over the entire recessed face and having holes adapted to connect with the recesses, 75 one face of said ejector plate forming a separating line of the mold.

2. In a mold for metal castings, an article retaining part having cavities therein, 80 a non-retaining part separable from the retaining part, and an ejector plate between said mold parts having openings larger than the cavities of the first mentioned part.

3. In a mold for metal castings, an article retaining part having cavities therein, a 85 non-retaining part separable from the retaining part and having cavities therein larger than the first mentioned cavities and an ejector plate between the mold parts having openings smaller than the second 90 mentioned cavities.

4. In apparatus for casting articles, a mold divided into two parts, one of said parts having a greater tendency to retain the articles than the other, and an ejector 95 plate between said parts, said ejector plate being movable with the part having the less retaining tendency and adapted to retain the articles when withdrawn from the last mentioned part.

5. In apparatus for casting articles, a mold divided into two parts, one of said parts having a greater retaining tendency than the other, an ejector plate between said parts adapted to prevent the articles from 105 being drawn therefrom by the retaining part, means for separating the ejector plate and the retaining part from the other part and means adapted to engage the ejector plate to separate it from the retaining part 110 after the mold parts have been separated.

6. In apparatus for casting articles, a mold divided into two parts, one of said parts having a greater retaining tendency than the other, means for separating the 115 mold parts, an ejector plate between said parts adapted to prevent the articles from being drawn therefrom by the retaining part, said ejector plate having a plurality of slots, a plurality of pins co-operating with 120 said slots for holding the ejector plate between said parts of the mold, said pins being adapted to retain the ejector plate after the parts of the mold are separated.

7. In apparatus for casting articles, a 125 mold divided into two parts, said parts having different relative draft whereby the article is retained in one part, means for separating the mold parts, an ejector plate between said parts adapted to prevent the 130

articles from being drawn from said ejector plate by the retaining part of the mold and means for suspending the ejector plate from the non-retaining part adapted to permit a limited movement of the ejector plate after the mold parts are separated whereby the articles are removed from the retaining part of the mold.

8. In apparatus for casting articles, a mold divided into a non-retaining and a retaining part, a stationary vertical frame for

the non-retaining part, a pivoted frame for the retaining part, an ejector plate between the two mold parts having a plurality of slots, a plurality of pins on said stationary ¹⁵ frame for suspending the ejector plate, said pins having heads adapted to allow limited movement of the ejector plate with the retaining part of the mold.

In testimony whereof, I hereunto affix ²⁰ my signature.

C. W. HAZELETT.
